UNITED STATES PATENT OFFICE.

DANIEL E. ASHER, OF GOSPORT, INDIANA.

GRAIN-DRILL.

SPECIFICATION forming part of Letters Patent No. 231,749, dated August 31, 1880.

Application filed April 24, 1880. (No model.)

To all whom it may concern:

Be it known that I, DANIEL E. ASHER, a citizen of the United States, residing at Gosport, in the county of Owen and State of Indiana, have invented certain new and useful Improvements in Grain-Drills; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention has for its object to simplify the construction and increase the efficiency of seeding-machines; and it consists in certain novel constructions and combinations of parts, as hereinafter fully described, and shown in 20 the accompanying drawings, in which—

Figure 1 is a side elevation with one of the drive-wheels removed. Fig. 2 is a top-plan view with the seed-hopper removed and parts of the frame broken away. Fig. 3 is a top-plan view of one of the cups. Fig. 4 is a vertical transverse section, and Fig. 5 a side elevation, of the same. Fig. 6 is a vertical transverse section of the fertilizer-hopper.

Like letters of reference are employed in the 30 above figures of drawings to indicate like parts wherever such may occur.

A represents the main frame, composed of the longitudinal girts a , a forward transverse girt, a' , intermediate transverse girt, a^2 , and a rear transverse girt, a^3 . B are the drive-wheels, mounted upon an axle, b , from which the machine is supported. C is the draft-bar bolted to the girts a' a^2 , as shown in dotted lines, Fig. 2, and full lines, Fig. 1. D is the driver's 40 seat, which is here mounted, in the usual manner, upon the girt a^3 at the extreme rear end of the machine, so that the weight of the driver will assist to counterbalance the weight of the forward end of the frame and relieve the horses 45 from said weight, and in this respect differs from all other machines of this class.

E represents the seed-spout rail hung from a bow or yoke, F, by means of links f , whereby said rail, together with the seed-spouts and 50 other devices supported thereby, may be raised

and lowered by the driver in his seat operating the hand-lever f' . The transverse arm of the yoke is so located as to provide a rest for the driver's feet, to enable him to hold the seeding devices to their work, which is especially advantageous in heavy soils. 55

The rail E has a series of slots, through which pass the supporting-standards e' , to adapt them for lateral adjustment by means of the set-screws e^4 , for the purpose of regulating the width of the rows. 60

G are the seed-spouts, secured to the standards e' by means of clevises g , and to said seed-spouts are bolted the furrow-plows H, the lower end or point of which is forked to receive the heel end of the drags I. 65

The standards e' are screw-threaded at their upper and lower ends for the reception of the nuts e^2 e^3 , the former serving to support the standards in the slots of the rail, and the latter as a bearing for the clevises g . 70

Between the clevises g and the rail E the standards are surrounded by a coiled spring, g' , or they may be surrounded by rubber springs to adapt the devices supported from 75 said standards to yield vertically.

In machines of this class as heretofore constructed, when one of the plows encountered an obstruction, the driver had to raise the whole series of plows and seed-spouts out of 80 the ground to avoid said obstruction after having first stopped his team, and by this means was not always able to prevent injury to the particular plow or plows or seed-spouts. By the application of the springs above described each plow is adapted to yield when 85 encountering an obstruction, thereby avoiding not only the raising of the series of plows from the ground, but also any injury to said plows. 90

I represent drags or furrow-cleaners, which are branched at their rear end, as shown by Fig. 1, leaving an open space between the plows H and the branches i i' , as shown at i^2 in Fig. 1, the heel branch I being secured between the forked point of the plow H and the branch i' to the upper end of the plow and the lower end of the seed-spout by means of a sleeve or clevis, i^3 , and a bolt, i^4 . 95

The furrow-cleaners I are of curvilinear form, 100

and are attached at their forward end to bracket-arms I' , connected to and forming with the blocks I^2 bearings for the forward end of said furrow-cleaners, which bearings are adjustably mounted upon a shaft, J , at the forward end of the machine.

It will be seen that when the plows and seed-spouts are adjusted laterally upon the rail E , to regulate the width of the rows, the forward end of the furrow-cleaners may be correspondingly adjusted by means of the set-screws I^3 , and the opening i^2 at the heel end of the drags prevents any accumulation of trash to choke the plows and interfere with the cutting of a clean furrow, which is of great importance, as this feature of construction obviates a great deal of annoyance and saves considerable time and labor required in all other machines for occasionally removing the accumulated trash in front of the plow.

The shaft J is hung in bearings J' , depending from the forward end of the girts a , and said bearings are so arranged that the furrow-cleaners may be adjusted vertically either by providing said bearings with a series of apertures, j , for the passage of the shaft, as shown in Fig. 1, or by any other preferred means, such as a bearing block or blocks held within a slot in said bearings, between which the shaft is held, and adjusted vertically by means of set-screws. These furrow-cleaners, as will be readily seen, assist materially in overcoming obstructions. Their curvilinear form immediately in front of their heels adapts them, and with them the plows and seed-spouts, to readily ride over obstructions, while the attachment of these cleaners and their plows to the seed-spouts is such that the plows may be readily removed for sharpening or repair, as will be readily understood.

The rail E is guided in its vertical movements by segmental guides E' , secured to the girts a and forked guide-plates e^5 , as shown by Figs. 1 and 2, secured to said rail E .

The supporting-rail is so arranged that when depressed or lowered upon its pivotal points, which are practically the bow F and shaft J , the plow-points will be on a line with the axis of the drive-wheel shaft. This is another important feature, inasmuch as it requires much less power to move the machine over the field than would be the case if the plow-points were on a line in rear of said shaft, as will be readily seen.

K' , Fig. 1, are the delivery-tubes, and M the seed-cups, and K the seed-hopper, mounted upon the machine and connected with each other in any usual or preferred manner.

The seed-hopper carries in front a grass-seed hopper, k , and I mount thereon in rear the fertilizer distributer or hopper L , which consists preferably of a cylindrical receptacle running the whole length of the seed-hopper, and connected with the seed-spouts by means of delivery-tubes, or the connection may be made direct with the seed-hopper, though I prefer

the former arrangement. This fertilizer-distributer L , Fig. 6, is provided with a series of delivery-ports, l , and a corresponding number of cut-off valves, e' , connected to a valve-rod, e^2 , by means of which the quantity of fertilizer delivered may be regulated, said valve-rod being connected with the usual gaging devices, and may be operated in any convenient manner by means of a lever within reach of the driver in his seat.

To facilitate the delivery of the fertilizer, and to adapt the machine to sow comminuted manure, I employ a series of stirrers, L' , mounted on a shaft, l^3 , rotated from the gear-wheel b' , Fig. 2, on the drive-wheel axle b and suitable intermediate gearing.

M , Figs. 3, 4, and 5, represents the seed-cups, of usual form and connected with the seed-hopper and seed-spouts in the usual or any preferred manner, and connected together at their lower ends by means of a line-shaft, m .

N is the seed-wheel, having a series of seed-cups, n , arranged in inclined rows upon the periphery of said seed-wheel. These seed-wheels are mounted upon a line-shaft, M' , driven from gear-wheel B' on the drive-wheel axle b , intermediate gear-wheel, B^2 , and the pinion B^3 upon said line-shaft.

The gear-wheel B^2 is supported upon the forward end of a lever, R , said forward end being mounted upon the main shaft b , while the rear end of said lever has a fork embracing an eccentric, P , mounted upon the outer end of the crank-arm f^2 of the yoke F , the crank-arm f^3 of which carries the hand-lever f' .

It will be seen that by this arrangement, when the lever f' is thrown backward to raise the rail and parts supported thereby, the toothed wheel B^2 will be thrown out of gear with the pinion B^3 to stop the delivery of seed simultaneously.

O is the cut-off valve, composed of a semi-cylindrical shell, o , surrounding one-half of the seed-wheel, and of a width equal to two-thirds of the width of said wheel when the latter has three rows of cups, and passing into the seed-cup through a suitable slot formed in the side thereof.

The valve has a rearwardly-projecting bearing, O' , through which and a like bearing in the seed-cups passes the line-shaft S . Said line-shaft passes loosely through the seed-cup, while the valves are rigidly connected therewith by means of set-screws o' .

The shaft S may be operated in any desired manner by means of a hand-lever, s , Fig. 2, within reach of the driver in his seat, to uncover two or more of the seed-cups to regulate the quantity of seed to be sown.

Having now described my invention, what I claim is—

1. In a seeding-machine, the combination, with the seed-spouts and furrow-plows, of furrow-cleaners having their heel end branched to form an open space immediately in front of

said plows, substantially as and for the purpose specified.

2. The combination of the seed-spouts G, plows H, and the adjustable furrow-cleaners 5 I with the shaft J, slotted rail E, standards E', and set-screws e^4 and I^3 , substantially as described, and for the purpose specified.

In testimony whereof I affix my signature in presence of two witnesses.

DANIEL E. ASHER.
